CLAIM

The ornamental design for a writing tablet, as shown and described.

DESCRIPTION

FIG. 1 is a top perspective view of a writing tablet showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the writing tablet that form no part of the claimed design. The depth of the sliding slot defined in the top surface of the writing tablet forms no part of the claimed design.

1 Claim, 8 Drawing Sheets
